CHOKE STRUCTURE FOR GUN BARRELS

Lee H. Wright, Grosse Pointe, Mich.

Application May 4, 1945, Serial No. 591,920

10 Claims. (Cl. 42—79)

1

This invention relates to a gun choke and has to do particularly with a choke for the barrel of a shot gun.

The desirability of a choke construction in the barrel of a shot gun is well known to those versed in the art of manufacturing and versed in the use of the gun. Suffice it to say that the choke of a barrel is a controlling factor in governing the shot pattern. A barrel with no choke, that is a cylinder bored barrel provides a relatively wide pattern of the shot at a given distance. In other words, the shot spreads. A similar barrel with a choke keeps the shot from spreading so much with the result that at the same distance the pattern is relatively smaller and the shot are more closely related. A skilled hunter can tell whether or not he wants a choked action in taking a particular shot and, suffice it to say, often it is desirable to have no choke, or little choke, when the first shot is fired at a game bird or other game animal, but to have a choke action for subsequent shots because the game is moving away. Experienced hunters frequently own several barrels or guns, each bored differently for obtaining different choke actions or for no choke action at all and the two barrels of a double-barrel shot gun are frequently arranged so that one has no choke structure.

The present invention aims to provide an improved gun barrel choke construction which may be constructed as an attachment to be mounted upon a gun barrel or which may be constructed and manufactured as a part of the gun barrel. In accordance with the invention, an automatic action is obtained. For example, the structure may be initially set so that when the gun is first fired there is no choking action. And upon the second or subsequent shots being fired, there is a choking action. The operation of the choke takes place automatically and incident to the forces developed in the firing of a gun. As will be seen later, it is thought that this action is due to the recoil. The invention also aims to provide a construction which is capable of adjustment so that the choking action obtained may be governed by the will of the user, or so that the structure may be locked in any given position so that the same condition prevails through a sequence of fired shots with a substantially equal choking or no choking as desired.

Other objects of the invention will become apparent and will be better understood as the following detailed description is considered with the accompanying drawings:

Fig. 1 is a side elevational view of the end of

2

a gun barrel with the choke construction applied thereto with some parts cut away to show the interior structure.

Fig. 2 is a view similar to Fig. 1 showing the choke structure shifted to choke position.

Fig. 3 is an enlarged cross sectional view taken substantially on line 3—3 of Fig. 1 with the structure in non-choking position.

Fig. 4 is a further enlarged cross sectional view illustrating the parts in choking position.

Fig. 5 is a view illustrating the barrel extension which provides choking action.

Fig. 6 is an end elevational view looking at the left hand end of Fig. 5.

Fig. 7 is an enlarged detail of one of the rotary adjusting cam elements.

Fig. 8 is a detailed view of the catching mechanism.

Fig. 9 is an enlarged sectional view showing a form where the structure is incorporated directly in a gun barrel.

As illustrated in Fig. 1, the barrel of a shot gun is shown at 1 with its normal end illustrated at 2. When the choke is to be attached to a barrel, as illustrated in Figs. 1, 2 and 3, it is preferred that the barrel be cylindrically formed internally so that it has no normal choking action in and of itself.

Mounted on the barrel is a barrel extension member 3. Preferably, this member telescopes over the end of the barrel. To mount the member the end of the barrel is preferably externally threaded and its end may be reduced somewhat in thickness and the extension is internally threaded, the cooperating threads being illustrated at 4. To hold the extension in place so that it does not turn on the barrel, the extension on the barrel may be pinned together as at 5. As illustrated in Fig. 5, the extension is provided with an element 6, provided with a detent 7. The forward portion of the extension is reduced in exterior diameter so as to provide a shoulder 8 and a bearing surface 9. The end of the extension is provided with a plurality of slots 10 to thereby form between each pair of slots a yieldable finger or segment 15. These slots, as shown in Fig. 6, are preferably of V-shape with the V-structure opening outwardly. As a result the edges of the segments meet substantially at line contacts as shown at 16. These segments are formed so that they normally are in choking position with the segments contacting or substantially contacting at the line contacts 16. The segmented portion is formed with a raised bead-like structure adjacent its end providing a contact surface 17, which

55

is inclined as shown, and another inclined contact surface 18 located approximately mid-way along the length of the segments. Between the areas of contact 17 and 18, the segments have surfaces 19.

A controlling structure is mounted over this extension. This structure, in the forms shown in Figs. 1 to 4 is fabricated from a number of parts, including an exterior sleeve 20. There is a forward internal sleeve 22 with an internal inclined contacting surface 23; there is an intermediate sleeve member 24 with an internal contacting surface 25. The surfaces 23 and 25 are angularly disposed so as to cooperate with the surfaces 17 and 18. There is another inner or ring-like member 26 arranged to slide on the surface 9 while the right hand end of the piece 20 slides on the surface 21. The sleeve or ring members 22, 24 and 26 are united to the exterior sleeve 20 so that all move in unison. The sight 27 may be in the form of a rivet or key for holding the ring 22 in place and a pin 28 may hold the ring 26 in place. The sleeve 20, adjacent its right hand end, as Fig. 3 is viewed, is of somewhat thicker metal than its remaining portion and it is provided with a slot 30 which slidably fits over the element 6 on the extension. This holds the parts against turning and yet permits the outer control member to slide axially relative to the extension piece 3.

Mounted on the outer control member 20 is a stud 31 which serves as a fulcrum for a member in the nature of a rack or ratchet. This member is generally illustrated at 32 and it has inclined teeth 33 for cooperation with detent 7. The member 32 has a thumb piece 34, which when pressed raises the rack from the detent 7. A spring 35 which is secured to the post 31 normally presses the ratchet so that it engages the detent 7.

There are two rotary cam-like adjustable devices rotatably mounted on the outer member 20 and these are positioned on opposite sides of the key 6. One of these members is shown in Fig. 7 and it is in the form of a split ring, generally illustrated at 40 having a roughened or knurled operating edge 41. The split is illustrated at 42. The axially extending portion, as illustrated at 43, gradually increases in width so as to provide a cam surface 44. Thus, except for a relatively flat spot 45 and a relatively flat spot 46, the surface 44 is inclined throughout its extent. The other cam member 40a has a similar inclined surface 44a. These two split ring members may be identical, and one, at 40a, is positioned against the shoulder 50 on the outer member and the other 40 is in reversed position adjacent a shoulder 51 on the end of the control member. The split rings have internal beads 47 fitting in grooves as shown which hold them against longitudinal displacement. Accordingly, it will be seen by reference to Figs. 1 and 2, that the outer control member may shift axially within limits determined by the key 6 and the cam surfaces. The split ring member 40 serves to close the slot 30 so that the key member is confined therein. It will be appreciated that by rotating the members 40 and 40a that the extent of axial movement of the outer or control member is limited. As shown in Figs. 1 and 2 the axial extent of movement is approximately maximum.

In the form of device shown in Fig. 9, the parts are essentially the same as those already described but the device is incorporated directly in the gun barrel construction. Accordingly, the

parts have the same reference characters applied thereto with the addition of a prime, where the parts differ. In this form the gun barrel 1 has the slotted segmental structure 15' formed integrally thereon. The outer or control member 20' is made of one piece instead of an assembly of parts having the contact surface 23', the contact surface 25' for cooperation with the surfaces 17' and 18'. The other parts have the same reference characters applied thereto.

In using the construction, it may be adjusted to a position as shown in Figs. 3 or 9. In this position, the control member is shown shifted forwardly. This is done by pressure upon the thumb piece 34, which lifts the ratchet teeth 33 from the detent 7 and by manually shifting the control member forwardly. In this position the rack engages the detent to hold the member 20 against longitudinal movement during normal handling of the gun. It will be noted that at this time the contact faces 23 and 25 are spaced from the faces 17 and 18 of the segmented portion. However, the segmented portion is in its choked position. This is the normal position for the segmented portion. When a shot is fired the internal pressure, which may be partially due to the gas pressure, or the force or action of the discharge of the shot and its plug, etc., causes the segments 15 to expand. There is nothing to hold the segments in their choked position so they readily expand into the contact surfaces 23 and 25. Now, this extent of expansion may be controlled by the user. In other words, the expansion depends upon how far forward the control member is shifted. This can be governed by the rotary position of the control ring 40. The substantially maximum forward position is shown in Fig. 1. In this position it is preferable that the action is comparable to a cylinder bore wherein there is no choking action. If a slight choking action is desired for the first shot, the control member may be shifted to the right from the position shown in Fig. 1 and its position determined by the rotatable adjustment of the member 40 as the element 6 abuts the cam surface 44. This brings the surfaces 23 and 25 in closer relationship to the surfaces 17 and 18 to limit the expanding action of the segments 15 as the first shot is made. When the gun is fired there is a reaction or kicking action which tends to throw the gun backwardly as the charge is projected forwardly. This is met and overcome by the shoulder of the user. Immediately following the kicking of the gun the user's shoulder rebounds. This action causes the outer control member to shift inwardly relative to the gun barrel and the inclined surface 44a of member 40a strikes element 6. The extent to which the control member thus shifts is determined by the rotary position of the element 40a. This, then, results in a choked action for the succeeding shot. Any time the control member shifts inwardly relative to the barrel, as above described, the teeth 33 operate over the detent 7. In order for the control member to be shifted outwardly relative to the barrel, the rack must be manipulated to be released from the detent. The member 40a can be adjusted to bring the most narrow portion thereof into alignment with the element 6 so that movement of the control member inwardly of the barrel as the gun is fired for the first shot is such that the surfaces 23 and 24 make contact with the surfaces 17 and 18 and thus provide for a maximum choke.

The parts are now in the position shown in

Fig. 4. When the gun is again fired the segmented portions are held in choking position as the segments cannot expand. However, the position shown in Fig. 4 is for maximum choke. If it is desired that the parts assume a position short of maximum choke then the ring 40a is adjusted to limit the rearward motion of the control element. By making this adjustment the desired clearance may be obtained for the expansion of the segmented portions before they come into contact with the holding surfaces 23 and 25 or 23' and 25' in the case of the modified construction. It is believed that probably the action which causes the telescoping action of the control member from the Fig. 1 position to or toward the Fig. 2 position is the rebound action of the physical structure or shoulder of the user of the gun. It all happens so quickly that as yet it is not known, what does cause this action, although it appears that the above explanation is plausible. The sudden gun movements incident to the firing of the gun in conjunction with the inertia of the control element provides the automatic adjusting action. As the control member shifts following the firing of the first charge, the teeth 33 slide along the detent 7 and the teeth latch upon the detent and hold the control member in its shifted position. In order to reset the structure it is only necessary to depress the finger piece 34 so that the rack releases the detent whereupon the control member may be shifted forwardly to the Fig. 1 position.

It will be observed that the segmented choking portion is always in a normal choking position and that the choke action is obtained by restraining the segments against outwardly flexing or expanding. It will also be observed that this restraining action can be regulated so that it comes into effect at any place between the maximum and minimum choke. In a twelve-gauge gun, for example, the diameter of a cylinder bored barrel is about .729 inch. A full choke may present a diameter of about .694 inch which would be measured at the ends of the segments when in their normal or collapsed position as shown in Fig. 3. These figures are, of course, variable insofar as this invention is concerned. The cam or flange portions 43 are preferably of such width that the two rings 40 and 40a can be relatively adjusted so as to grip the key 6 therebetween and thereby lock and hold the control member against axial movement. Thus the structure can be set or locked in elected positions from substantially no choke position to full choke position. A vent 55 may be employed so that air or gas will not be trapped ahead of the shiftable part, to thus insure the automatic action.

In the full choke position there is a surface to surface contact of the surfaces 17 and 18 with the interior surfaces of the sleeve. If the sleeve be advanced forwardly a trifle, the surfaces are separated and then if the segments be expanded they engage the interior of the sleeve with only a line contact. However, in the full open position, as shown in Figs. 3 and 9, the angles are so preferably arranged that the intermediate portion 19 of the segments will have a surface contact with the interior of the sleeve for a considerable axial extent when the segments are expanded against the sleeve. An example of the angular disposition of the surfaces is as follows, the angularity being given with respect to the barrel axis: The angle of the surface 23, $4^{\circ} 2'$; the normal angle of the surface 17 when the segments are contracted, $4^{\circ} 2'$; the angle of the surface 19, $3^{\circ} 21'$; the angle of the surface 25, $2^{\circ} 2'$; the normal angle of sur-

faces 18, $2^{\circ} 2'$ when the segments are normally contracted.

The construction of the segmented choking portion is considered to be of importance particularly as to the shape of the notches defining the segments to provide a line contact between the segments and the fact that the segments are normally in contact with each other. In a construction of this kind, there may be various particles of matter such as carbon deposits or other extraneous material or substance which comes from the wadding or packing of the shells which may get in the slots between the segments and prevent their normal action of contraction. Any such material which gets into any one of the slots 10 can move freely into the widened V-portion so as to not block the slot in open position. Thus, under normal circumstances the segments will always come together at the line contact. This is advantageous also in the cleaning of the gun as the slots are normally closed and the cleaning cloth is not liable to be caught between the segments.

Moreover, when the segments are in their normal position, inclining toward each other, they substantially contact with each other throughout their length along the sharp knife edge meeting portions. When the segments flex outwardly the slots between the segments open up more near the free ends of the segments than at the base of the segments. Therefore, the slots or spaces between the segments at any time when they are partially open present a diverging opening as distinguished from a converging opening. Accordingly, the structure minimizes or eliminates the shaving of shot which may slide along the edges and materially reduces the catching of wadding or the like.

I claim:

- 40 1. A choke structure for a gun barrel comprising, a barrel member having a segmented end constituted by a plurality of circumferentially arranged segments defined by intervening lengthwise extending slots, said segments converging toward their free ends and normally lying in choking position with the slots substantially closed and adapted to flex outwardly under pressure, means mounted on the barrel member for axial sliding movement and adapted to slide by forces caused in firing the gun, said means having surfaces for embracing the exterior of the segments when the said means slides to one position to hold the segments against outward flexing whereby to cause a choking action.
- 45 2. A choke structure for a gun barrel comprising, a barrel member having a segmented end constituted by a plurality of circumferentially arranged segments defined by intervening lengthwise extending slots, said segments converging toward their free ends and normally lying in choking position with the slots substantially closed and adapted to flex outwardly under pressure, and control means slidably mounted on the barrel member having internal surfaces spaced from the segments in one position and embracing the exterior of the segments in another position to hold the segments against outward flexing, said control means adapted to shift relative to the barrel member by forces incident to firing
- 50 3. A choke structure for a gun barrel comprising, a barrel member having a segmented end constituted by a plurality of circumferentially arranged segments defined by intervening lengthwise extending slots, said segments converging toward their free ends and normally lying in choking position with the slots substantially closed and adapted to flex outwardly under pressure, and control means slidably mounted on the barrel member having internal surfaces spaced from the segments in one position and embracing the exterior of the segments in another position to hold the segments against outward flexing, said control means adapted to shift relative to the barrel member by forces incident to firing
- 55 4. A choke structure for a gun barrel comprising, a barrel member having a segmented end constituted by a plurality of circumferentially arranged segments defined by intervening lengthwise extending slots, said segments converging toward their free ends and normally lying in choking position with the slots substantially closed and adapted to flex outwardly under pressure, and control means slidably mounted on the barrel member having internal surfaces spaced from the segments in one position and embracing the exterior of the segments in another position to hold the segments against outward flexing, said control means adapted to shift relative to the barrel member by forces incident to firing
- 60 5. A choke structure for a gun barrel comprising, a barrel member having a segmented end constituted by a plurality of circumferentially arranged segments defined by intervening lengthwise extending slots, said segments converging toward their free ends and normally lying in choking position with the slots substantially closed and adapted to flex outwardly under pressure, and control means slidably mounted on the barrel member having internal surfaces spaced from the segments in one position and embracing the exterior of the segments in another position to hold the segments against outward flexing, said control means adapted to shift relative to the barrel member by forces incident to firing
- 65 6. A choke structure for a gun barrel comprising, a barrel member having a segmented end constituted by a plurality of circumferentially arranged segments defined by intervening lengthwise extending slots, said segments converging toward their free ends and normally lying in choking position with the slots substantially closed and adapted to flex outwardly under pressure, and control means slidably mounted on the barrel member having internal surfaces spaced from the segments in one position and embracing the exterior of the segments in another position to hold the segments against outward flexing, said control means adapted to shift relative to the barrel member by forces incident to firing
- 70 7. A choke structure for a gun barrel comprising, a barrel member having a segmented end constituted by a plurality of circumferentially arranged segments defined by intervening lengthwise extending slots, said segments converging toward their free ends and normally lying in choking position with the slots substantially closed and adapted to flex outwardly under pressure, and control means slidably mounted on the barrel member having internal surfaces spaced from the segments in one position and embracing the exterior of the segments in another position to hold the segments against outward flexing, said control means adapted to shift relative to the barrel member by forces incident to firing
- 75 8. A choke structure for a gun barrel comprising,

ing, a barrel member having a segmented end constituted by a plurality of circumferentially arranged segments defined by intervening lengthwise extending slots, said segments normally converging toward their free ends and normally lying in choking position and adapted to flex outwardly under pressure, and control means slidably mounted for axial movement on the barrel member having internal surfaces spaced from the segments in one position and embracing the exterior of the segments in another position to hold the segments against outward flexing, said control means adapted to shift relative to the barrel member by forces incident to firing of the gun and adjustable means for limiting the sliding stroke of the control means.

4. A choke structure for a gun barrel comprising, a barrel portion having a segmented end constituted by a plurality of circumferentially arranged segments defined by intervening lengthwise extending slots, said segments converging toward their free ends and normally lying in choking position and adapted to flex outwardly under pressure, and control means slidably mounted on the portion having internal surfaces spaced from the segments in one position and embracing the exterior of the segments in another position to hold the segments against outward flexing, said control means adapted to shift relative to the barrel portion by forces incident to firing of the gun, adjustable means for limiting the sliding stroke of the control means, said adjustable means being operable to lock the control means in a selected position to hold the control means against shifting.

5. A choke structure for a gun barrel comprising, a barrel portion having a slotted end defining segments, said segments being yieldable and normally converging toward the end of the barrel portion so that the sides of the segments are normally in contact with each other and a sleeve slidably mounted on the barrel portion for axial sliding movement, the sleeve and segments having cooperating surfaces which are spaced relatively widely apart when the sleeve is at one end of its movement and which approach each other as the sleeve moves toward the other end of its movement, said sleeve adapted to shift relative to the barrel portion by forces incident to firing the gun in a direction such that the cooperating surfaces move toward each other.

6. A choke structure for a gun barrel comprising, a barrel portion having a slotted end defining segments, said segments being yieldable and normally converging toward the end of the barrel portion so that the slots are normally substantially closed and a sleeve mounted on the barrel portion for axial sliding movement, the sleeve and segments having cooperating surfaces which are spaced relatively widely apart when the sleeve is at one end of its movement and which approach each other when the sleeve moves toward the other end of its movement, said sleeve adapted to shift relative to the barrel portion by forces incident to firing the gun in a direction such that the cooperating surfaces move toward each other, said surfaces on the segments and sleeve being inclined relative to the barrel axis.

7. A choke structure for a gun barrel comprising, a barrel portion having a slotted end defining segments, said segments being yieldable and normally converging toward the end of the barrel portion and substantially contacting each other and a sleeve mounted on the barrel portion for

axial sliding movement, the sleeve and segments having cooperating surfaces which are spaced relatively widely apart when the sleeve is at one end of its movement and which approach each other when the sleeve moves toward the other end of its movement, said sleeve adapted to shift relative to the barrel portion by forces incident to firing the gun in a direction such that the cooperating surfaces move toward each other, releasable means for holding the sleeve in an axial position constructed and arranged so that the sleeve will move in one direction by reason of forces incident to firing the gun.

8. A choke structure for a gun barrel comprising, a barrel portion having a slotted end defining segments, said segments being yieldable and normally converging toward the end of the barrel portion and substantially in contact with each other and a sleeve slidably mounted on the barrel portion, the sleeve and segments having cooperating surfaces which are spaced apart when the sleeve is at one end of its movement and which are in substantial contact when the sleeve is at the other end of its movement, said sleeve adapted to shift relative to the barrel portion by forces incident to firing the gun from a position where the surfaces are out of contact to a position where the surfaces are in substantial contact, adjustable means for limiting the stroke of axial movement of the sleeve, said adjustable means being operable to lock the sleeve in various axial positions and to hold the same against sliding movement.

9. A choke structure for a gun barrel comprising, a barrel portion having a segmented end constituted by a plurality of circumferentially arranged segments defined by intervening lengthwise extending slots, said segments converging toward their free ends and normally lying in choking position and adapted to flex outwardly under pressure, control means slidably mounted for axial movement on the barrel portion having internal surfaces spaced from the segments in one position and embracing the exterior of the segments in another position to hold the segments against outward flexing, said control means adapted to shift axially relative to the barrel portion by forces incident to firing the gun, ratchet means for holding the control means in a set position and operable for sliding movement of the control means upon firing of the gun and adjustable limit means for limiting the sliding stroke of the control means.

10. A choke structure for a gun barrel comprising, a barrel portion having a segmented end constituted by a plurality of circumferentially arranged segments defined by intervening lengthwise extending slots, said segments converging toward their free ends and normally lying in choking position and adapted to flex outwardly under pressure, control means slidably mounted for axial movement on the barrel portion having internal surfaces spaced from the segments in one position and embracing the exterior of the segments in another position to hold the segments against outward flexing, said control means adapted to shift axially relative to the barrel portion by forces incident to firing the gun, ratchet means for holding the control means in a set position and operable for sliding movement of the control means upon firing of the gun and adjustable limit means for limiting the sliding stroke of the control means, said adjustable limit means being adjustable to lock the

control means against sliding action in one of various elected positions of adjustment.
